UNITED STATES PATENT OFFICE.

OTTO BRUNNER, OF SAIMANNSLEHEN, AUSTRIA-HUNGARY.

SCREW-PROPELLER FOR AEROPLANES, AIRSHIPS, VESSELS, AND THE LIKE.

1,105,753.

Specification of Letters Patent.

Patented Aug. 4, 1914.

Application filed February 15, 1913. Serial No. 748,567.

To all whom it may concern:

Be it known that I, Otto BRUNNER, of Saimannslehen, Lower Austria, in the Empire of Austria-Hungary, a subject of the Emperor of Austria-Hungary, have invented certain new and useful Improvements in and Relating to Screw-Propellers for Aeroplanes, Airships, Vessels, and the like; and I do hereby declare the following to be a full, clear, and exact description of the invention, such as will enable others skilled in the art to which it appertains to make and use the same.

This invention relates to screw propellers for aeroplanes, airships, sea-going vessels, and the like, and it has for its object the construction of screw propellers for these purposes based upon the idea of forming that active part (hereinafter called the front part) of the vane surface which first impinges upon the surrounding medium, and which is, in the sense of rotation of the vane, on the front side thereof, in such manner that substantially all the particles of the surrounding medium impinging upon it are reflected or diverted in a certain manner into the immediate proximity of another part (hereinafter called the rear part) of the active vane surface, whereby a condensation of the medium is produced at the rear part so that the rear part moves in a denser medium and has its effect increased. However, the front and rear parts are formed so that they direct the particles of the medium as completely as possible against a peripherally added surface (hereinafter called the peripheral part) with a projection directed backward relatively to the direction of movement, to thereby cause also a condensation of the medium and thereby increase the action of the screw. It has been found by experiments that these conditions are met by a screw propeller wherein the front part of its vane or vanes consists of a conoidal surface, having its apex in the axis of the screw, having its generating line formed by a cycloid segment, and having its leading line formed by an arm of a parabola opening in the direction of movement, the axis of the parabola being situated in the plane of rotation, that is, in a plane perpendicular to the axis of the screw, and a screw exit surface, forming the rear part, which is generated by the movement of the cycloid segment along the axis of the screw and along a line extending obliquely backward,

being connected to the conoidal surface. Preferably, a vane projection, rounded off peripherally backward and arranged on the outer or peripheral part of the vane, extends in a direction opposite to that of the rotation of the propeller. Vane projections have been used heretofore, but in the present case the vane projection has an added function in that the condensed medium sliding along the cycloid segment is pressed under it, whereby an increased upward movement or forward movement is obtained.

In order that this invention may be better understood, I now proceed to describe it with reference to the accompanying drawings illustrating a constructional form of a vane for a propeller, in which—

Figure 1 represents an elevation of a vane for a sea-going vessel; Fig. 2 represents a plane of the active surface of the vane of Fig. 1, showing also several cross sections of the vane taken at different points; Fig. 3 represents a side elevation of the vane of Fig. 1; Fig. 4 represents a well known method of constructing a cycloid by rolling a circle along a straight line; Figs. 5, 6, 7 and 8 are similar to Figs. 1, 2, 3 and 4, but illustrate the constructional form of a vane for an airship.

The hub L, which is connected to a driving shaft (not shown) driven by any suitable source of power such as an internal combustion engine, is provided with a suitable number of vanes. The construction of the active surfaces of these vanes constitutes the subject matter of the present invention, the backside of the vanes being formed in any convenient manner and not being a part of this invention.

The principles on which the construction of my vane is based are as follows: It is well known that a cycloid is the brachistochrone of a body moving under a constant force from one point to another point. As previously stated, the purpose of my construction is to cause the particles of the medium impinging upon the active vane surface to move to the peripheral part of the vane, and to do this I form the passages for the particles of the medium from the center to the periphery of the vane in the shape of a cycloid in order that those particles pushing on the vane near the center thereof are led as quickly as possible toward the peripheral part. Furthermore all particles of the medium impinging upon the

front part of the vane should be reflected in such manner as to obtain a condensation of the medium where the rear or exit part of the vane acts. Now, it is well known that a surface having a cross section in the form of a parabola reflects all particles which move parallel to the axis of the parabola and which contact with the surface toward the focus of the parabola. Thus, I make the cross section of the front part of the active surface of the vane in the form of an arm of a parabola, whereby when the vane rotates all particles of the medium impinging upon that front part are reflected in the manner hereinbefore described.

In accordance with my invention, the active surface of the vane may be formed as follows, reference being had to Figs. 1 to 4 for the propeller vane of a sea-going vessel, 20 and to Figs. 5 to 8 for a propeller vane of an airship; assume that a horizontal plane A A is passed through the vane and that there is placed therein a cycloid B D (Figs. 2 or 6) which has one point coincident with the center of the hub L and which has been formed by rolling a circle of radius B C (Figs. 4 or 8) along a straight line. Upon rotating the line B D about the center B (Figs. 2 or 6), each point of the line B D 25 describes a circle. Thus the point E describes the circle E Z having a radius E B. This circle represents the section of a vertical cylinder of radius E B cut by the horizontal plane A A. Suppose now that a parabola having the point F on its arm be 30 constructed in a vertical plane, the vertex of the parabola being at E and the axis being in the horizontal plane and forming a tangent to the circle; and further suppose that the plane of the parabola is bent in such 35 a way that the parabola falls into the surface of the vertical cylinder whose base is E Z. The point F'' will be displaced thereby to the point F. If now the cycloid E is moved, its point E traveling along the parabola E F and its point B being fixed at the center of the arm, a conoidal surface will be produced, and the generating line of this 40 conoidal surface is the cycloid segment, while the leading line of the conoidal surface is 45 the line E F of the parabola which opens in the direction of rotation of the vane. 50 If vertical cylinders having radii B G, B H and B E, respectively, be brought to 55 intersect the vane with their axes coincident with that of the hub, the lines of intersection with the active surface of the vane will coincide with the parabolas G I', H K' and E F' after the cylinder surfaces have been 60 flattened or pressed into vertical planes so that the points I, K and F lie at I'', K'' and F'', and afterward are turned down from the vertical position into the horizontal position along the lines G I'', H K'', and E F'', respectively.

The rear part of the active vane surface is generated by moving the cycloid segment B E with its free end along a line E M which leads from the point E obliquely backward, whereby a screw surface is obtained. The lines G N', H O' and E P' are the lines of intersection with the vertical cylinders above mentioned after flattening and turning them down. In order to have a surface which is entirely smooth and without any line of fracture or any reentering line, the front part of the vane is suitably curved out near the line of juncture with the rear part, as shown in Figs. 2 and 6. The lines of intersection with the vertical cylinders may be, for instance, I' Q N', K' O' and F' R P', respectively.

To the front and rear parts of the vane, there is annexed peripherally the third or peripheral part having toward its rear, in the sense of movement of the vane as indicated by the arrow in Figs. 2 and 6, a vane projection rounded off peripherally backward. The active surface of that part of the vane is more or less a plane, and is generated by gradually flattening the curved front part of the vane. The plane of intersection of this part with a cylinder of radius B S flattened or stretched out, and turned down at a right-angle in the same manner as described in connection with the front and rear parts of the vane, presents the shape of a plano-convex lens, as illustrated in Figs. 2 and 6, the plane corresponding to the active surface being T U, 90 and the backside being T D U.

If the screw propeller shown in Figs. 1 to 4 or Figs. 5 to 8 be turned in the direction of the arrow of Figs. 2 or 6, all particles of the medium impinging upon the conoidal 105 surface parallel to the axis of the parabola forming its base are reflected to the line of the foci W. This medium is condensed there, so that the screw surface moves in a condensed medium, its forward or upward driving action thereby being increased. Simultaneously, however, the particles of the medium are for the most part pushed away against the vane projection D U'' U, in consequence of the cycloidal form of the generating line forming the shortest path, 110 whereby the action of this part of the vane is increased also.

In the foregoing, the parts of the vanes have been described separately for the sake 120 of clearness, but it will be understood that in general all of these parts may be made of one piece of wood or metal. The vane may consist of wood or metal, and the backside thereof may be formed in any suitable manner. The shape of the cycloid, as well as the form of the parabola, is dependent upon the medium in which the vane is to rotate, and is also dependent upon the predetermined speed and of the material of the vane, all of 125 130

which may be easily determined by experiments. In applying the invention to screw propellers for sea-going vessels, the thickness of the vane, that is, the distance between opposite points on the active surface and backside of the vane, should generally be greater than in the case of vanes for airships.

Experiments have shown that a screw propeller constructed in accordance with my invention produces an upward or forward action, approximately 30% greater than that of a screw propeller constructed according to the Ressel system.

Having thus described my invention, what I claim is:

1. In a vane for screw propellers, a front part having an active surface, and a rear part having an active surface, the active surface of the front part being shaped to reflect substantially all the particles of the impinging medium into immediate proximity to the active surface of the rear part; substantially as described.

2. In a vane for screw propellers, a front part having an active surface, a rear part having an active surface, and a peripheral part formed peripherally of said parts, the active surface of the front part being shaped to reflect substantially all of the particles of the impinging medium into immediate proximity to the active surface of the rear part, and the active surfaces of the front and rear parts being shaped to direct the particles of the impinging medium against the active surface of the peripheral part; substantially as described.

3. In a vane for screw propellers, a front part having an active surface, a rear part having an active surface, and a peripheral part formed peripherally of said parts and having a projection extending in a direction opposite to that of the movement of the vane, the active surface of the front part being shaped to reflect substantially all of the particles of the impinging medium into immediate proximity to the active surface of the rear part, and the active surfaces of the front and rear parts being shaped to direct the particles of the medium against the active surface of the peripheral part; substantially as described.

4. In a vane for screw propellers, a front part having an active surface of conoidal

form with its apex in the axis of rotation 55 of the propeller and its generating line formed by a cycloid segment and its leading line formed by an arm of a parabola open in the direction of movement and having its axis in the plane of rotation of the vane, 60 and a rear part adjoining the front part and consisting of a screw surface for the exit of the impinging medium; substantially as described.

5. In a vane for screw propellers, a front 65 part having an active surface of conoidal form with its apex in the axis of rotation of the propeller and its generating line formed by a cycloid segment and its leading line formed by an arm of a parabola open in the 70 direction of movement and having its axis in the plane of rotation of the vane, and a rear part adjoining the front part and having a screw active surface for the exit of the impinging medium, said screw surface 75 being formed by the movement of the cycloid segment along the axis of the propeller and along a line extending obliquely and in a direction opposite to that of the movement 80 of the vane; substantially as described.

6. In a vane for screw propellers, a front part having an active surface of conoidal form with its apex in the axis of rotation 85 of the propeller and its generating line formed by a cycloid segment and a leading line formed by an arm of a parabola open in the direction of movement and having its axis in the plane of rotation of the vane, a rear part adjoining the front part and having a screw active surface for the exit of 90 the impinging medium, said screw surface being formed by the movement of the cycloid segment along the axis of the parabola and along a line extending obliquely in a direction opposite to that of the movement 95 of the vane, and a peripheral part added peripherally to the front and rear parts and having a projection extending rearwardly relatively to the direction of movement of the vane, the peripheral part being rounded 100 off peripherally; substantially as described.

In testimony whereof I affix my signature, in presence of two witnesses.

OTTO BRUNNER.

Witnesses:

JOHANN LUX,
AUGUST FUGGER.

It is hereby certified that in Letters Patent No. 1,105,753, granted August 4, 1914, upon the application of Otto Brunner, of Saimannslehen, Austria-Hungary, for an improvement in "Screw-Propellers for Aeroplanes, Airships, Vessels, and the Like," an error appears in the printed specification requiring correction as follows: Page 2, line 44, for the word and reference letter "cycloid E" read *cycloid E F*; and that the said Letters Patent should be read with this correction therein that the same may conform to the record of the case in the Patent Office.

Signed and sealed this 29th day of September, A. D., 1914.

[SEAL.]

R. F. WHITEHEAD,

Acting Commissioner of Patents.
